UNITED STATES PATENT OFFICE

2,560,849

IRONING BOARD

Paul F. Dahlstrom, La Grande, Oreg.

Application October 6, 1948, Serial No. 53,038

1 Claim. (Cl. 38—121)

1

This invention relates to a collapsible ironing board.

An object of this invention is to provide a collapsible ironing board embodying pivotally connected together legs with an improved means whereby the legs are spring-tensioned to leg extending position with one of the legs formed at its upper end into a pawl engageable in a selected one of a series of notches which are formed in the top so that the top may be raised or lowered to the desired height.

Another object of this invention is to provide an ironing board which in collapsed form will occupy only a small space.

With the above and other objects in view, my invention consists in the arrangement, combination and details of construction disclosed in the drawings and specification, and then more particularly pointed out in the appended claim.

In the drawing:

Figure 1 is a bottom plan view partly broken away and in section of an ironing board constructed according to an embodiment of this invention.

Figure 2 is a sectional view taken on the line 2—2 of Fig. 1.

Referring to the drawing the numeral 10 designates generally the top of an ironing board constructed according to an embodiment of this invention. The board or top 10 is supported in vertically adjusted position by means of a pair of crossed legs designated generally as 11 and 12. The leg 11 is hinged by means of a hinge 13 to the top 10 adjacent an end of the top, and the leg 11 is formed of a pair of elongated bars 14 which have secured to the lower ends, thereof, a connecting foot piece 15.

The leg 12 comprises an elongated bar 16 which is disposed between the bars 14 and pivotally mounted on a pivot 17 extended through the bars 14. A pair of spacing members 18 are secured to the inner sides of the bars 14 for spacing the bars 16 relative to the inner edges of the bars 14. The leg bar 16 has secured to the lower or outer end thereof a foot member 19 similar to the foot member 15 and the inner or upper end of the leg bar 16 is formed as a pawl 20 for engagement in a selected one of a series of notches 21 which are formed in the lower side of the top 10. The upper end of the leg member 16 is slidably disposed with respect to the top 10 by means of a pair of U-shaped guide bars 22 which are fastened in depending relation to the lower side of the top 10 on opposite sides or ends of the notches 21. The pawl 20 has mounted, therethrough a

pin 32 projecting from the opposite sides of the pawl and engaging within the guide 22.

The legs 11 and 12 are normally biased to an extended position by means of a spring 23 which is mounted in a channel or recess 24 formed in the lower side of leg member 16, and one end of spring 23 is fastened by fastening means 25 to the lower end of channel 24, and the other end of spring 23 has secured thereto a flexible member 26. The flexible member 26 is extended through an opening 27 formed in leg member 16, being trained over a grooved pulley 28, rotatably disposed in opening 27. The flexible member 26 is then extended upward and is secured by fastening means 29 to the lower side of top 10 between guide 22 and hinge 13.

In the use and operation of this ironing board, the board is collapsed by raising the same to disengage pawl 20 from one of the notches. The board may then be collapsed by pushing the same downwardly. In order to extend the legs, the structure may be placed in collapsed position on a floor with the board 10 uppermost, whereupon the board 10 may be lifted upwardly. When board 10 is lifted upwardly, spring 23 will pull leg member 12 and leg member 11 to extended position with pawl 20 sliding over the notches 21. When the top 10 has been raised to the desired height, the weight of the top alone will provide for engagement of the pawl 20 in an adjacent notch or keeper 21.

What is claimed is:

A collapsible ironing board comprising a top board, a pair of crossed legs, means hingedly securing the upper end of one leg to the lower side of said top board, means pivotally securing said legs together at their crossing point, said top board having a series of notches in its lower side, a transversely extending pawl carried by the other of said legs engageable in a selected one of said notches, a pin extending transversely through said pawl, means forming a recess in said other leg, a flexible member extending lengthwise of said other leg, one end of said flexible member extending below said pivot means, a spring secured at one end to said one end of said flexible member and seated in said recess, means comprising a headed pin securing the other end of said spring to said other leg adjacent the outer end of the latter, said other leg having an opening therethrough above said pivot means, a grooved pulley rotatably disposed in said opening, said flexible member being trained over said pulley and extended upwardly toward said top board, means securing the other end of said flex-

ible member to said top board between said hinge means and said notches, and a pair of U-shaped guide bars disposed on opposite sides of said series of notches, extending a substantial distance therebeyond to permit collapsing of said legs and spaced apart a distance greater than the width of said pawl, but less than the length of said pin whereby said pawl is always retained within said guide bars adjacent said series of notches.
